CLAIM

The ornamental design for a handheld multifunction appliance for multiple functions including a brush, as shown and described.

DESCRIPTION

FIG. 1 is a right side view of a handheld multifunction appliance for multiple functions including a brush according to the present application;

FIG. 2 is a left side view thereof;

FIG. 3 is a front view thereof;

FIG. 4 is a rear view thereof;

FIG. 5 is a top view thereof;

FIG. 6 is a bottom view thereof;

FIG. 7 is a front, bottom perspective view thereof; and,

FIG. 8 is a front, top perspective view thereof.

In the drawings, the broken lines showing a brush attachment illustrate environment and form no part of the claimed design. The remaining broken lines illustrate portions of the handheld multifunction appliance forming no part of the claimed design.

1 Claim, 7 Drawing Sheets(56)
